UNITED STATES PATENT OFFICE.

JOHN LIVINGSTONE, OF TORONTO, ONTARIO, CANADA.

MEANS FOR ASSURING PERFECT COMBUSTION.

SPECIFICATION forming part of Letters Patent No. 427,432, dated May 6, 1890.

Application filed June 20, 1889. Serial No. 314,911. (No model.)

To all whom it may concern:

Be it known that I, JOHN LIVINGSTONE, manufacturer, residing at 31 York Chambers, Toronto Street, in the city of Toronto, Province of Ontario, and Dominion of Canada, have invented Improvements in Means for Assuring Perfect Combustion, of which the following is a specification.

This invention is an improvement upon that for which I obtained a patent dated March 12, 1889, No. 399,541.

My invention relates to that class of devices by which steam is introduced into the furnace to aid combustion.

15 It is for use as a part of or as an attachment to furnaces of every kind for the purpose of increasing the efficiency of the furnace and the perfect combustion of the fuel.

It is for the decomposition of the steam into 20 its gaseous parts and ejection into the furnace.

It is for use to accelerate motion among the particles uniting in combustion in the furnace.

25 The form of the device and parts thereof is and are of necessity varied as to shape according to the size and kind of each furnace or boiler, according to the room-space available, and where available on a boiler, in a 30 boiler, in a furnace, or in a place in close proximity thereto for any part of the device.

The nature of my invention will more fully appear from the subjoined description, and the novelty will be pointed out in the claims, 35 reference being had to the accompanying drawings of one form of the device, in which it is made to apply to a portable boiler of the locomotive type.

Figure 1 is a longitudinal section of a boiler, 40 showing the furnace and my apparatus connected thereto. Fig. 2 is a transverse view of a boiler with the front plates of the boiler removed, so as to show the inside of a furnace and part of my apparatus (the superheaters) 45 therein. Fig. 3 is an enlarged section of the superheaters D D with combination therein.

Fig. 4 is an enlarged section of superheaters D D with no combination therein, and Fig. 5 50 a view showing the device applied to a furnace having hollow perforated grate-bars.

A in Figs. 1 and 2 is a vessel that may be of any shape to suit the space or place avail-

able, made of boiler-plate or cast-iron or other suitable material, of strength to resist internal pressure equal to that in the same boiler 55 to which it is attached or of which it may be a part, and in it is stored scrap zinc or zinc strips or pieces of zinc, finely-divided particles of iron and metal filings, turnings, and small pieces of scrap metal. 60

B is a steam-pipe from the boiler, entering A and passing through it. The portion inside of A is surrounded by one or more tubes, tunnels, or pipes b' b², of iron or brass or other suitable metal, with holes in the said 65 portion of B inside of A and in the surrounding pipes b' b², as seen in Fig. 1, exposed for reference to the perforations and woven linings hereinafter referred to around b' b². The said portion of B and the surrounding pipes 70 b' b² may be each incased in close-fitting sleeves made of fine woven-wire cloth, or the sleeves may be made of flannel, cotton, canvas, or other suitable woven material. The sleeves may be made fast to the said 75 portion of the pipe B, and the sleeves for each of the said pipes b' b² may be made fast by sewing each sleeve, according to its size or pipe, to each respective pipe with fine wire of brass or other metal through the holes in 80 the said portion of the pipe B and through the holes in the surrounding pipes b' b² within the vessel A, as seen in Fig. 1.

Between A and the boiler the pipe B is fitted with a check-valve b³ and a shut-off 85 valve b⁴ for disuse of the invention when for any cause necessary to use the boiler without the device; but the check-valve is more especially to prevent gases entering the boiler.

C is a pipe connected to A, by which oil 90 may be put into the vessel A by hand or by any mechanical device. A glass gage may be used to show the level of oil in the vessel A, and a hand-hole with secure joint may be in any part of the said vessel A to remove 95 sediment or refuse matter.

D (see Figs. 1 and 4) represents superheaters of any desired shape or form, according to the room-space and shape of the space available. I prefer the cylindrical form of a 100 size corresponding to the available room-space in the furnace. They may be about seven to ten inches in diameter, placed in the preferred part, the part preferred being on each side of

the door at the front inside, standing on end, resting upon the floor of the furnace, and passing up through the grate-bars, or standing upon the grate-bars, (see Fig. 2,) or supported by any suitable means, and of such height as may be suitable for the furnace. D D may be made of cast-iron or suitable metal. I prefer a fire-resisting quality of cast-iron, which may be protected by a coating or by any suitable means. I prefer the use of the metal without any coating or cover, and the superheaters D must be of sufficient strength to withstand pressure at least equal to that in the boiler.

15 Inside the casings of D D there may be tubes E E, of iron, or steel, or brass, or bronze, or other suitable material, that may pass through the upper end to the bottom of the inside. (See Fig. 3.) The bottoms of the casings of D D and the tubes E E are closed and steam-tight. The inner tubes E E may be about one-third of the diameter of the outer shells D D and have a number of small holes, which may be in parallel rows, drilled through 20 the sides of each about half an inch apart. (See Fig. 3.)

Around tubes E E and close-fitted thereto may be sleeves of fine woven brass wire-cloth sewed to said tubes E E, with brass wire 30 stitched through the holes in the tubes to the sleeves in which tubes are incased, and within the tube is also a lining of fine woven brass wire-cloth, also stitched to tubes with brass wire through the holes in E E. (See Fig. 3.)

35 From the inner linings in the tubes E E, but not passing through the said linings, (see Fig. 3,) there may be one or more (see Fig. 1) small tubes or nozzles F F F, made to project through from the linings (see Fig. 3) within 40 and through E E and outer linings of the tubes and through the superheaters D D on the circle or in angles one to the other, exposing to the fire short blunt or semicircular points F F F. (See Fig. 1 for each superheater.)

45 The opening in the inner end of each of the nozzles or tubes F F F for about half an inch or less may be one sixty-fourth of an inch in diameter or less, increased by tapering the hole in each nozzle toward the outer 50 or semicircular end, say, to the extent of about three thirty-seconds of an inch in diameter at the furnace end or point, (see Fig. 3,) for the purpose of blowing through any grit or sediment that may pass to the nozzles F F F, as seen in the sectional view of upper F, Fig. 3.

Instead of nozzles there may be holes, which may be made to taper through superheater D, like those in the nozzles.

The nozzles or tubes F F F in superheaters 60 D D are made to project, as stated, by being screwed through the casing of superheater D D and tube E E, (see Fig. 3,) or they may be made to screw through superheater D D (see Fig. 4) without the combination therein, 65 as seen in Fig. 3.

Within the spaces (see Fig. 3) between the

brass woven wire-cloth lining to tube E E and the casings D D there are placed loosely small pieces of metal and iron or steel, iron filings, iron turnings from iron turning-lathes, 70 and scrap metals in small particles.

The holes or nozzles F F F in each of the superheaters D D (see Fig. 2) are placed one above the other, (see Fig. 3,) the lowest being about ten inches above the grate-bars, so as to be a little above the level of the top of the fuel when coal is used, and I place the others each about four inches above the other; but they may be on the circle of D or at angles thereon one to the other.

80 The holes in superheaters or nozzles F F F are adjusted to point diagonally across the furnace; but the particular angle is not essential, nor is the height at which they are placed, as both may be varied to suit conditions required by the shape and size of the furnace or kind of fuel used.

B' is a continuation of steam-pipe B, which may have a check-valve and a shut-off valve (see Fig. 1) from the boiler through A and connecting A with the inner tubes E E. (See Figs. 1, 2, and 3.) By means of it steam is conveyed into superheaters D D. (See Fig. 2.)

H is a movable pipe, so arranged that when necessary it may be used to increase the 95 draft above the fire-bed or to prevent any excess of volume in the gases escaping through the door, (see Fig. 1,) or it may be extended to aid in creating a draft-current through hollow grate-bars in the furnace, as a steam-jet, (see O, Fig. 5,) if hollow grate-bars be used with air or gas vents in the form of small holes, slots, or slits into the furnace through the fuel.

The operation of the device is as follows: 105 After steam has been raised to a pressure in the boiler it is passed through the pipe B to the vessel A, (see Fig. 1,) and from A by the pipe B' to the brass tubes E E within and to the superheaters D D, (see Figs. 1 and 2,) the 110 steam carrying in its course its units of heat, acting upon and acted upon by the heated metal or iron turnings, filings, or pieces of iron and steel in A and in the spaces in the superheaters between the linings of E E and 115 casings of D D and upon the superheaters D D, and, therein becoming superheated in contact with the iron, particles of iron, and metal, is decomposed into its component parts, and expelled by pressure through the 120 holes or nozzles F F F into the furnace above the fire-bed in the form of combustible gas energized by the heat and pressure, accelerating motion among the particles in motion in the furnace and uniting by affinity 125 with the carbon of the solid fuel for perfect combustion in the union of all the particles of combustion.

Air may be admitted through the grate-bars, as in ordinary firing, or naturally through 130 hollow grate-bars with holes or slots in the upper side of each or any number of the

grate-bars, rests, or head or end pieces in contact with the fuel. The air passing naturally through the hollow grate-bars may be accelerated in motion by a steam-jet from movable 5 pipe H.

When desirable, always by preference at low temperatures, and preferably as increasing efficiency at all temperatures, the vessel A is partially filled with oil, by preference 10 crude petroleum, which, acted upon by the heat from the steam passing through B, gives off a vapor thinned by filtration through the sleeve-linings on the pipes $b' b^2$, that in smallest measure saturates the steam from the 15 boiler, overcoming and counteracting the aqueous properties of the steam at low temperatures, increasing the gases in the furnace, and aiding combustion.

I do not herein claim the grate-bars shown 20 in Fig. 5, as that forms the subject-matter of a separate application, Serial No. 308,941, filed April 29, 1889.

Having now particularly described and ascertained the nature of my said invention and 25 in what manner the same is to be performed, I declare that what I claim is—

1. The combination of the boiler, the vessel A, having metal strips, scraps, or particles therein, the pipe B, leading from the steam-dome of said boiler through vessel A to the 30 fire-box and having that part passing through vessel A perforated, and the superheater in said fire-box and connected with pipe B, substantially as described.

35 2. The combination of the boiler, the ves-

sel containing zinc or composition zinc strips, scraps, or particles, the pipe B, leading from the steam-dome of said boiler through vessel A to the fire-box and having that part passing through vessel A perforated, and the superheater in said fire-box and connected with 40 pipe B.

3. The combination of a boiler, the vessel A, containing metallic scrap or particles, the pipe B, leading from the steam-dome of said boiler through vessel A to the fire-box and having that part passing through vessel A 45 perforated, and the superheater containing iron or steel filings or similar substances in contact with the steam and connected with 50 said pipe B, substantially as described.

4. The combination of the vessel A, the steam-pipe passing through said vessel and having the part in the vessel perforated, and the close-fitting sleeves made of fine wire-cloth or flannel inclosing said perforated part 55 of the steam-pipe, substantially as described.

5. The combination of a boiler, the vessel A, containing metallic scrap, the pipe B, leading from the steam-dome of said boiler through 60 vessel A to the fire-box and having that part passing through vessel A perforated, the superheater connected with said pipe B, the hollow grate-bars, and the steam-jet O in said grate-bars, substantially as described.

JOHN LIVINGSTONE.
